VENTILATED COVER FOR A MOTORCYCLE SEAT

Robert E. Flowers, Rte. 1, 3 Mile Lake Bayshore Drive,
Paw Paw, Mich. 49079

Filed Sept. 30, 1974, Ser. No. 510,237

Term of patent 14 years

Int. Cl. D12—11

U.S. Cl. D6—191

Fig. 1

Fig. 2

Fig. 3

Fig. 4

FIG. 1 is a top plan view of a ventilated cover for a motorcycle seat showing my new design;

FIG. 2 is a right side elevational view thereof, the opposite side being a mirror image of the right side shown herein;

FIG. 3 is a front elevational view thereof; and

FIG. 4 is a rear elevational view thereof.

The bottom of the ventilated cover is substantially unornamented.

I claim:

The ornamental design for a ventilated cover for a motorcycle seat, substantially as shown and described.
